His Attorney.

UNITED STATES PATENT OFFICE.

JOHN E. CONZELMAN, OF ST. LOUIS, MISSOURI, ASSIGNOR, BY MESNE ASSIGNMENTS,
TO UNIT CONSTRUCTION COMPANY, A CORPORATION OF DELAWARE.

CONCRETE CONSTRUCTION.

961,211.

Specification of Letters Patent. Patented June 14, 1910.

Original application filed January 9, 1909, Serial No. 471,431. Divided and this application filed April 29, 1909. Serial No. 492,862.

To all whom it may concern:

Be it known that I, JOHN E. CONZELMAN, a citizen of the United States, residing at the city of St. Louis, State of Missouri, have 5 invented certain new and useful Improvements in Concrete Construction, of which the following is a specification, reference being had therein to the accompanying drawings.

- 10 This invention relates to concrete building structures, and pertains to the class of structures set forth and described in my co-pending application for patent, Serial No. 471,431, filed Jan. 9, 1909, of which this application is a division. The structures set forth therein refer to buildings in which concrete slabs are used for ceilings and floors, and are supported at their corners or intermediate points by uprights or columns.
- 15 It is the object of this invention to provide a structure of concrete building elements which coöperate and are interengaged to form a rigid, secure and lasting jointure of said elements.
- 20 It is also an object to provide a concrete building structure in which the general construction of the coöperating uprights and horizontal members is generally improved, to present a neat appearance as well as to
- 25 prove of strong and durable nature.

In the drawings, which form a part of this specification and in which like numbers of reference indicate like parts, Figure 1 is a longitudinal section taken through the 35 supporting columns and slabs, and Fig. 2 is a sectional view taken on line 1—1 of Fig. 1. 1 indicates a column forming one of the upper supporting members of a building structure, and resting upon a lower column 40 13. Column 1 is formed in the plastic state with its base formed within casting 2, a casting having internal, integral rings 3 forming grooves 4, in which the concrete flows and in which it hardens, thus making 45 it extremely difficult to separate the base of said column from said casting 2. A flange 5, turned inwardly from casting 2, contributes to the same end. On the exterior of casting 2, flange 6 is provided, said flange 50 having perforations 7, through which bolts 8 pass. The casting 2 rests on a plate 9 having perforations 10 and being seated on the upper end of column 13. Bolts 8 pass through said perforations, and into a cap 12

formed on column 13, said plate being anchored to stud 11 on cap 12 of column 13, by anchor bolts 14 passing through said plate 9 and extending deeply into the concrete of said cap, which sets with said anchor bolts embedded therein. 55

By the construction above described, a rigid and durable joint is secured between the abutting ends of the columns 1 and 13, and means is provided for the support of the horizontal members of the building construction. 60

Having thus described my said invention, what I claim and desire to secure by Letters-Patent is:

1. A concrete construction, comprising, in combination, a supporting column, a cap formed around the upper portion of the column below the top thereof, slabs seating on said cap and having their upper sides disposed flush with said top of said column, 75 a second column superposed upon said supporting column, a plate seating on top of said supporting column and extending over onto the upper sides of said slabs, means to anchor said plate to the supporting column, 80 and means to secure said second column to said plate.

2. A concrete construction, comprising, in combination, a supporting column, a cap formed around the upper portion of the 85 column below the top thereof, slabs seating on said cap and having their upper sides disposed flush with said top of said column, a second column superposed upon said supporting column, a plate seating on top of 90 said supporting column and extending over onto the upper sides of said slabs, a casting inclosing the lower end of said second column, an outstanding peripheral flange carried by said casting, and bolts extending 95 through openings provided therefor in said flange and plate whereby the two columns are rigidly connected.

3. A concrete structure, comprising in combination, a supporting column, a cap 100 formed around the upper portion of said column below the top thereof, slabs having their edges seated on said cap and having the upper end of said supporting column, a second column superposed upon said supporting column, a casting surrounding the base 105 of said second column, and forming a part

thereof, and means for securing said casting to said supporting column.

4. A concrete structure, comprising in combination, a supporting column, a cap surrounding the upper portion of said column, below the top thereof, a plate resting on said column and extending over the top thereof, slabs having their edges seated on said cap and below said plate, a casting 10 bolted to said plate and a second column having its base molded within said casting.

5. A concrete structure, comprising in combination a supporting column, a cap formed on said supporting column below the top 15 thereof, a plate seated on the top of said column and extending over the edges of said

top, bolts entered through said plate and extended into said supporting column, slabs having their edges seated on said cap and below said plate, and a casting having internal ribs seated on said plate and having an external flange, bolts entered through said plate and said external flange to secure said casting to said plate, and a column having its base molded within said casting. 20 25

In testimony whereof I have affixed my signature in presence of two witnesses.

JOHN E. CONZELMAN.
